CLAIM

The ornamental design for a mobility scooter as shown and described.

DESCRIPTION

FIG. 1 is a front, top, and left perspective view of a mobility scooter showing my new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is a bottom plan view thereof;

FIG. 8 is a rear, bottom, and right perspective view thereof;

FIG. 9 is an enlarged view of the portion indicated with the number 9 in FIG. 6;

FIG. 10 is a perspective view of the mobility scooter when it is folded as a whole;

FIG. 11 is a perspective view of FIG. 10 with the basket removed; and,

FIG. 12 is a perspective view of a mobility scooter with the front basket removed and the lockbox in a folded position. The dot-dash broken lines encircling an enlargement portion of the design forms no part of the claimed design.

1 Claim, 12 Drawing Sheets
